ROOFING

Vernon Tatro, Chicago, Ill.

Application February 19, 1940, Serial No. 319,619

14 Claims. (Cl. 108—7)

The invention relates generally to roofing and more particularly to an individual shingle element and to the method of laying the same.

A general object of the invention is to provide a shingle element of new and improved construction and shape.

A more particular object of the invention is to provide a shingle element of such proportions and dimensions that it may be laid in a variety of ways producing different patterns or designs on the roof with each manner of laying providing sufficient overlap to assure a leakproof construction.

Another object is to provide a single element having markers for aiding in positioning and aligning the shingle elements in any one of the several ways of laying the same.

A further object is to provide a shingle element of unique proportions, having all its edges whole multiples of a common unit of length, facilitating manufacture and laying, and change in size of shingle while retaining the same ability and manner of laying to produce a variety of patterns.

Still another object is to provide a shingle element having a set off area in one corner which determines the overlap in the laying of the shingle and the spacing of the various markers.

Other objects and advantages will become apparent from the following detailed description taken in connection with the accompanying drawings, in which:

Fig. 1 is an elevational view of a shingle element embodying the features of the invention.

Fig. 2 is an elevational view similar to Fig. 1 but showing the element divided into units.

Fig. 3 is a view showing the manner in which the elements may be cut from a standard roll of roofing material.

Fig. 4 is a fragmentary view of a roof showing one manner of laying the shingle elements resulting in offset large and small squares.

Fig. 5 is a view similar to Fig. 4, but showing another method of laying the elements resulting in large squares only.

Fig. 6 is a view similar to Fig. 4, but showing still another method of laying the elements resulting in a generally parallelogram design.

Fig. 7 is a view similar to Fig. 4 but showing the shingle elements laid in a still further manner resulting in a diamond pattern.

While the invention is susceptible of various modifications and alternative methods of laying, it is here shown and will hereinafter be described in a preferred embodiment and several

ways of laying the same. However, it is not intended that the invention is to be limited hereby to the specific disclosure shown. On the contrary, it is intended to cover all modifications and alternative methods of laying the shingle element falling within the spirit and scope of this invention as defined in the appended claims.

As best seen in Figs. 1 and 2, each individual shingle element has a straight end edge 10 and straight side edges 11 and 12 parallel to one another and at right angles to the end edge 10. In the preferred embodiment here shown, these edges are whole multiples of a common unit of length. In the present instance, as best seen in Fig. 2, the end edge 10 and the side edge 11 are composed of four such units of length, while the side edge 12 is composed of five such units of length, it being understood, of course, that the length of the unit may be varied and that the number of units of length in each edge can be varied so long as certain proportions which will hereinafter become more apparent are maintained. The remaining end edge is irregular and is composed of end portions 13 and 14, each one unit in length and parallel with the end edge 10, and an intermediate diagonal portion 15. This diagonal portion does not extend strictly between the inner ends of the portions 13 and 14, but is swung slightly further from the vertical so as to form adjacent the portion 14 a projecting point 16 which serves as a gauge mark, and an indentation 17 adjacent the portion 13 forming an additional gauge mark. A gauge mark in the form of a small, triangular lobe 18 is formed in the side edge 11, and a gauge mark in the form of a triangular notch 19 is formed in the side edge 12.

Extending inwardly from the end edge 10 and parallel with the side edge 12 is a scoring 20 which, with the aid of the edges 10 and 12, indicates a square area which forms the basis for the spacing of the gauge marks 18 and 19, as well as the marks 16 and 17, and also predetermines the amount of overlap obtained in the laying of the shingle elements. An average extent of a suitable overlap is four inches and, accordingly, the scoring 20 has been made four inches long and thus the unit adopted in the present instance is four inches in length. As a result, the shingle element here shown is sixteen inches wide, and sixteen inches long at its edge 11, and twenty inches long at its edge 12. As has already been stated, the portions 13 and 14 of the irregular edge are each one unit in length and always maintain the same relationship to

the predetermined area, regardless of the other dimensions of the shingle element. Similarly, the gauge marks 18 and 19 bear a definite relationship in their spacing from the irregular end edge to the dimensions of the predetermined area. In the case of the gauge mark 18, it is spaced from the irregular end edge a distance equivalent to one side of the predetermined area or one unit, while in the case of the gauge mark 19 it is located directly beneath the mark 18 as viewed in Figs. 1 and 2, with the lower portion of the shingle element projecting a sufficient distance to the right as to space the portion 14 two units from the gauge mark 19.

While the shingle element may be formed from a variety of materials, the proportioning above described is particularly advantageous when the shingle element is composed of asphalt or asbestos, for then it may be cut from a standard roll of roofing without any loss whatsoever as is clearly shown in Fig. 3. The sum of the length of the sides 11 and 12 is equal to the width of the roll of roofing and thus two shingle elements may be cut from a rectangular portion of the roll of roofing. When so cut, the portion which is removed from one shingle element to form the projecting point 16 on the other element forms the indentation 17 of the first element. Similarly, with the gauge marks 18 and 19 disposed directly opposite one another, the portion of the roofing which is taken to form the lobe 18 is the same as that which would be cut from another shingle element to form the notch 19. Consequently, there is no waste whatsoever in the formation of shingle elements from the roll of roofing.

A shingle element proportioned as herein described adapts itself to laying in a variety of ways so as to produce a variety of different patterns upon the roof. Moreover, the shingle elements are readily laid, for the various gauge marks aid in properly alining and spacing the shingle elements with the result that not only is the laying of the shingle elements effected more easily and quickly, but a truer alinement of the shingle elements is obtained. One such manner of laying the shingle elements resulting in staggered large and small squares is disclosed in Fig. 4. When laid in the manner shown in Fig. 4, the end edge 10 forms the lower edge of the shingle element. The shingle elements are laid from left to right in Fig. 4, and, of course, the first course of shingles is composed of a repeated series of shingle elements of successively greater length. More specifically, the first course is normally started with a shingle element S1 which has been cut off along a line connecting the gauge marks 18 and 19. The second shingle S2 is composed of a shingle element which has been cut off one unit of length beyond the gauge marks 18 and 19, and is laid with its edge portion 13 coinciding with the edge portion 14 of the shingle element S1 and with its vertical side edge 11 alined with the marker 16 of the shingle element S1. Similarly, a shingle S3 cut off one unit of length inwardly from the end edge 10 is next placed over the shingle S2, again with the end edge portion 13 of shingle S3 coinciding with the end edge portion 14 of the shingle S2, and the side edge 11 of shingle S3 in alinement with the gauge mark 16 of the shingle S2. This process is continued until a full length shingle element is employed. In the present instance, inasmuch as the shingle element herein disclosed has a side edge 11 of four

units of length, the shingle S4 is such a shingle of full length and thus completes the series. As previously stated, the series is repeated starting with a shingle element S1' similar to the shingle element S1. The proper positioning of the shingle element S1' is readily obtained and the starting point of the second series is clearly indicated, for the side edge 11 of the shingle S1' coincides with the scoring 20 of the shingle S4.

After the first course has been laid, the second course is readily laid, for the various gauge marks not only clearly indicate the manner in which the shingle elements should be laid, but provide alining points against which the edges of the shingles either abut or with which they may be alined so as to assure uniformity in laying for obtaining an exact pattern and for maintaining the required and predetermined amount of overlap. Thus a shingle element S5 of the second course is placed with its end edge 10 in alinement with the gauge mark 18 of the shingle element S1, and with its side edge 12 in alinement with the gauge mark 16 or, more particularly, in abutment with the side edge 11 of the shingle element S2. A shingle element S6 is then placed in overlapping relation to the shingle element S5 in the same manner as the shingle element S2 of the first course was placed in overlapping relation to the shingle S1 of the first course, which, of course, also means placing the shingle S6 in the same relation to the shingle S2 as the shingle S5 assumes with respect to shingle S1. More particularly stated, shingle S6 is placed with its end edge 10 in alinement with the gauge mark 18 of shingle S2, its end edge portion 13 coinciding with the end edge portion 14 of the shingle S5, its side edge 11 in alinement with the scoring 20 and the gauge mark 16 of shingle S5, and its side edge 12 abutting the side edge 11 of the shingle S3. With four points or lines of alinement, there is thus little danger that the shingle element will not be properly placed and, of course, the speed at which it may be laid is greatly increased because the workmen can see at a glance whether or not the shingle element is in proper position.

Not only are the shingle elements readily laid in proper alinement, but they require a minimum of securing means to assure their proper attachment to the roof and to one another. When constructed and laid in the manner herein disclosed, each shingle element is secured by a nail 21 driven through the shingle element at its upper left hand corner, as viewed in Fig. 4. This nail will, of course, also pass through the shingle which is underneath, and thus is the equivalent of nailing the shingle at its upper right hand corner, as viewed in Fig. 4. A second and final nail 22 is driven through the triangular portion of the shingle element. The free, exposed corner of each shingle is secured by clipping in any conventional manner and preferably by a clip 23 which has a hook portion which engages over the side edge 12 of the shingle element immediately below and has a prong 24 which pierces the exposed shingle element and then is bent over securely to hold the exposed corner of the shingle. Thus it will be apparent from the foregoing that but two nails are required to secure the shingle thus further reducing to a minimum the time required in the laying of the shingle.

As is most clearly apparent from that portion of Fig. 4 in which the hidden edges of the shingle elements have not been indicated, the resulting

pattern is that of large and small squares running diagonally across the roof. The large squares are formed by the edges of the various shingle elements, while the three sides of the small squares are formed by edges of the shingle elements and the fourth is formed by the scoring 20. This scoring is made sufficiently prominent so that it is readily seen from the street. With the size of the small squares so formed determining, as previously stated, the extent of overlap, both vertical and horizontal, a sufficient overlap is substantially guaranteed automatically. If the small square is to be at all noticeable from the street, the manufacturer must necessarily make the square of a size such that it will provide a sufficient overlap to assure a properly constructed roof. It is also to be noted that with this shingle construction and manner of laying the small square could be given a different color from the remainder of the shingle so as to emphasize the design or pattern of the resulting roofing.

In Fig. 5 there is disclosed another manner of laying the shingle elements which results in large squares only. In this manner of laying, the shingle elements are disposed in the same position in which they are shown in Figs. 1 and 2, that is, with the side edge 12 forming the bottom edge of the laid shingle elements. The shingle elements are again laid from left to right, as viewed in Fig. 5, but herein whole shingle elements are used even for the first course. Thus, for the first course of shingles a shingle element S1 is laid with its side edge 12 parallel with the edge of the roof and is secured by a nail 25 driven through the shingle element slightly inwardly and upwardly from the gauge mark 19. The next shingle element S2 is placed with its side edge 12 coinciding with the side edge 12 of the shingle element S1 and with its end edge 10 coinciding with the gauge marks 18 and 19, so as to provide a substantially vertical overlap, which at no point is less than one unit of length. The exposed corner of this shingle element is secured in any suitable manner as by a clip 26 of conventional construction. Remaining shingle elements composing the first course are applied in similar manner. The shingle elements S5, S6, etc., forming the second course, overlap one another in the same manner as described for the shingle elements of the first course and also overlap the tops of the shingle elements of the first course to provide a horizontal overlap. Just as the gauge marks 18 and 19 provide an indication for the extent of vertical overlap, so the gauge mark 16 provides an indication for the extent of horizontal overlap. More particularly, the shingle element S5 of the second course is so placed that its end edge portion 14 coincides and, in fact, abuts the end edge 10 of the shingle element S2, which in turn coincides with the gauge marks 18 and 19 of the shingle S1, and with the gauge mark 16 coinciding with the tops or side edges 11 of the lower course of shingles. Thus by such actual abutment of portions of the shingle elements of the upper course with those of the lower course, they are readily placed in the proper position to produce the pattern desired without necessity of measuring or estimating on the part of the workman. It is to be noted that when the nail 25 is driven through the shingle elements forming the second course, it also pierces the shingle elements forming the first course and thus secures the shingle elements to the roof in

two places, though but a single nail is driven in the laying of each shingle element.

Fig. 6 shows still another manner of laying the shingle element herein disclosed as resulting in a generally parallelogram pattern. In this manner of laying, the shingles are inverted from the showing in Figs. 1 and 2, that is they are so placed that the side edge 12 becomes the top edge and so that the irregular end edge is at the left as viewed in Fig. 6. Moreover, in this manner of laying, the irregular end edge is exposed as distinguished from the portion of the shingle bearing the scoring 20. In this manner of laying the shingle elements, as in the manner disclosed in Fig. 5, even the first course is composed of whole shingle elements. Thus the shingle element S1 is placed on the roof with its side edge 11 coinciding with the edge of the roof and is secured to the roof by a single nail 27 driven through the shingle element at its lower right hand corner, as viewed in Fig. 6. A second shingle element S2 is then placed on the roof with its edges 11 and 12 coinciding respectively with the corresponding edges of the shingle element S1, and with its gauge marks 18 and 19 coinciding with the end edge 10 of the shingle element S1. The exposed corner of the shingle element S2 is again secured by means of a suitable clip 28 of conventional construction. Successive shingle elements completing the first tier are applied in like manner. Shingle elements S5, S6, etc. composing the second course are applied to provide a vertical overlap with one another in the same manner as the shingle elements of the first course and overlap the tops of the shingle elements of the first course to provide a suitable horizontal overlap. The extent of horizontal overlap of the shingle element S5 over the shingle element S1 is clearly indicated by the gauge mark 16 of the shingle element S1, while the horizontal position of the shingle element S5 with respect to the shingle element S1 is determined and indicated by the gauge mark 18. In this instance, the marks 16 and 18 of shingle elements S1 and S5, respectively, are made to coincide for a proper positioning of the shingle elements. It will be readily apparent, particularly from that portion of Fig. 6 in which the hidden edges of the various shingle elements are not indicated, that a staggered, generally parallelogram pattern results from this manner of laying the shingle elements.

Fig. 7 discloses still a further manner of laying the shingle elements, this time resulting in a diamond pattern. To that end, the shingle elements are placed at a diagonal, as best seen from a consideration of shingle elements S5, S6, etc. forming the second course of shingles. The shingle elements S1, S2, S3, etc. are of necessity trimmed off along a line extending from the gauge mark 19 to a point on the end edge 10 one unit inwardly from the side edge 11, in order to provide a straight edge coinciding with the edge of the roof. The shingle element S1 of the first course is, as stated, placed at a diagonal in such position that its gauge mark 19 coincides with the lower edge of the roof and so that the edge of the roof intersects the end edge 10 at a point one unit inwardly from the side edge 11. The next shingle element S2 of the first course is then placed in a similar position with respect to the edge of the roof and with its side edge 11 overlapping the side edge 12 of the shingle element S1. The extent of overlap is indicated to the workman by the gauge mark 16 on the shingle element S1, for side edge 11 of the shingle element S2 when properly laid

abuts the gauge mark 16 of the shingle element S1 and the portion of the side edge 10 which remains on the shingle coincides with the gauge marks 18 and 19 of the shingle element S1.

The shingle elements S5, S6, etc. forming the second course are laid with respect to one another the same as the shingle elements forming the first course and are laid with respect to the shingles of the first course so that the side edges 12 overlap the side edges 11. More specifically, the shingle element S5, for example, is positioned with its end edge 10 coinciding with the portion of the end edge 10 of the shingle element S1 which is retained, while its side edge 12 is made to coincide with the gauge mark 17 to determine the extent of overlap between the shingle elements S1 and S5. The shingle elements are secured by a single nail 29 which is driven through the upper left hand corner of the shingle elements, as viewed in Figs. 1 and 2. In the case of the courses, except the first course, this nail 29 pierces three shingle elements; the uppermost but still not final shingle through the upper left hand corner, as stated; the intermediate shingle at a point upwardly and to the right of the gauge mark 19; and the lowermost shingle element through the upper right hand corner, as viewed in Figs. 1 and 2. Thus, by the use of a shingle nail so located, each shingle element is secured to the roof at three places. The exposed and remaining corner is then secured by means of a suitable clip 30 of conventional construction. As just described, the shingle elements have been applied from left to right, but it is believed readily apparent that in this manner of laying they could just as readily be laid from right to left. The resulting structure would be identically the same, the shingle elements would be secured in the same manner, and the only difference would be in the gauge marks that would be employed to align the shingle elements.

It is believed apparent from the foregoing description that I have perfected a shingle element of unique construction having many advantages over prior shingle elements. Outstanding is the fact that I have devised a shingle element, certain portions of which if maintained in certain proportions to one another serve as guiding means in the laying of the shingle elements and assure a proper overlap, while permitting the other portions of the shingle element to be varied in size. My shingle element, moreover, may without modification in construction be laid in a variety of ways producing different patterns, and the laying of the shingle elements in each of such variety of ways is facilitated by various elements which serve as gauge marks indicating the proper positioning of the shingle elements. By the provision of gauge marks, not only is the laying of the shingle element facilitated, but serves to assure the laying of the shingle elements with the proper overlap because if improperly laid the gauge marks would indicate such improper laying and thus enable the proprietor of the building being roofed to check on the workman laying the roofing.

I claim as my invention:

1. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the

laying of the shingle element, and an irregular end edge including a portion adjacent each side edge parallel with said first named end edge and of a length equal to the spacing of said score mark from the longer side edge.

5 2. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the laying of the shingle element, and an irregular end edge including a portion adjacent each side edge parallel with said first named end edge and of a length equal to the spacing of said score mark from the longer side edge, and gauge marks at the inner end of each said irregular end edge portion.

10 20 3. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the laying of the shingle element, an irregular end edge including a portion adjacent each side edge parallel with said first named end edge and of a length equal to the spacing of said score mark from the longer side edge, and a gauge mark on the shorter side edge spaced from said irregular end edge a distance equal to the spacing of said score mark from the longer side edge.

15 30 35 4. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the laying of the shingle element, an irregular end edge including a portion adjacent each side edge parallel with said first named end edge and of a length equal to the spacing of said score mark from the longer side edge, and a gauge mark on the longer side edge spaced from said irregular end edge a distance equal to twice the spacing of said score mark from said longer side.

40 45 50 5. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the laying of the shingle element, an irregular end edge including a portion adjacent each side edge parallel with said first named end edge and of a length equal to the spacing of said score mark from the longer side edge, a gauge mark on the shorter side edge spaced from said irregular end edge a distance equal to the spacing of said score mark from said longer side edge, and a gauge mark on the longer side edge spaced from said irregular end edge a distance equal to twice the spacing of said score mark from said longer side.

55 60 65 6. A shingle element having a straight end edge, straight and parallel side edges at right angles to said end edge, one of said side edges being longer than the other, a score mark extending inwardly from said end edge parallel with the longer side edge and spaced therefrom a distance equal to the overlap desired in the laying of the shingle element, an irregular end edge

including a portion adjacent each side edge parallel with said first named end edge and of a length equal to the spacing of said score mark from the longer side edge, a projecting lobe on the shorter side edge spaced from said irregular end edge a distance equal to the spacing of said score mark from said longer side edge, and a notch on the longer side edge spaced from said irregular end edge a distance equal to twice the spacing of said score mark from said longer side.

7. A shingle element having a straight end edge, straight and parallel side edges at right angles to said end edge, a score mark extending inwardly from said end edge parallel with the side edges and spaced from one of the side edges a distance equal to the overlap desired in the laying of the shingle element, said score mark being equal in length to its spacing from the adjacent side edge and the adjacent side edge being longer than the opposite side edge by an amount equal to its spacing from said score mark, an irregular end edge including a portion adjacent each side edge parallel with said first named end edge and of a length equal to the spacing of said score mark from the longer side edge, and an intermediate portion extending generally between the inner ends of said first mentioned portions forming a notched gauge mark at one end and a projecting gauge mark at the opposite end, a gauge mark on the shorter side edge spaced from said irregular end edge a distance equal to the length of said score mark, and a gauge mark in the longer side edge spaced from said irregular end edge a distance equal to twice the length of said score mark.

8. A shingle element having a straight end edge, straight and parallel side edges at right angles to said end edge, and an irregular end edge including a straight portion adjacent each side edge parallel with said first named end edge and each of a length equal to the extent of overlap desired in the laying of a plurality of shingle elements, one of said side edges being longer than the other side edge by the length of one of said end edge portions.

9. Roofing of the character described comprising, in combination, a plurality of overlapping courses of shingle elements, each shingle element having a straight end edge, parallel side edges of unequal length, and an irregular end edge including straight end portions of equal length and parallel with said first named end edge, one such portion being adjacent each side edge, the elements of each course being laid with successive elements offset upwardly and with the shorter side edge overlapping the longer side edge of the preceding element predetermined distances determined by coincidence of the straight portion of the irregular end edge of the upper element with the straight portion of the irregular end edge of the lower element, the shingle element of each succeeding upper course being laid with its straight end edge overlapping the upper portion of the lower course shingle element to a minimum equal to the length of one of the straight portions of the irregular end edge and with its longer side edge abutting and extending parallel with the shorter side edge of the adjacent shingle element of the lower course.

10. Roofing of the character described comprising, in combination, a plurality of overlapping courses of shingle elements, each shingle element having a straight end edge, parallel side edges of unequal length, and an irregular end edge including straight end portions of equal

length and parallel with said first named end edge, one such portion being adjacent each side edge, a score mark extending inwardly from said straight end edge parallel with the longer side edge and spaced therefrom a distance equal to the length of one of the straight portions of said irregular end edge, a gauge mark in the shorter side edge spaced from the end edge a distance equal to the spacing of said score mark from the longer side edge, the elements of each course being laid with successive elements offset upwardly and with the shorter side edge overlapping the longer side edge of the preceding element predetermined distances determined by coincidence of the straight portion of the irregular end edge of the upper element with the straight portion of the irregular end edge of the lower element, the shingle element of each succeeding upper course being laid with its straight end edge overlapping the upper portion of the lower course shingle element to coincide with the gauge on the short side edge of the shingle element in the lower course and with its longer side edge abutting and extending parallel with the shorter side edge of the adjacent shingle element of the lower course.

11. Roofing of the character described comprising, in combination, a plurality of overlapping courses of shingle elements, each shingle element having a straight end edge, parallel side edges of unequal length, and an irregular end edge including a straight portion parallel with said first mentioned end edge and adjacent the longer side edge, said straight portion being of a length equal to the desired amount of overlap in the laying of the shingle elements, a gauge mark on the shorter side edges spaced from the irregular end edge a distance equal to the length of said end portion, the shingle elements of each course being laid with their side edges horizontal and with each successive shingle element overlapping the preceding element to an extent that its straight end edge coincides with said gauge mark, each shingle element as laid being secured with but a single nail, and each course overlapping the next lower course to the extent of the straight portion of said irregular end edge.

12. Roofing of the character described comprising, in combination, a plurality of overlapping courses of shingle elements, each shingle element having end edges one of which is straight, and parallel side edges extending at right angles to the straight end edge, a gauge mark at the end opposite said straight end edge spaced inwardly from a side edge a distance equal to the desired amount of overlap in the laying of the shingle elements, a gauge mark on each of the side edges lying in a line parallel with said straight end edge and with the gauge marks spaced from the end edge bearing the first mentioned gauge mark by a distance not less than the spacing of said first mentioned gauge mark from the adjacent side edge, the shingle elements of each course being laid with their side edges parallel and coincident and with each successive shingle element overlapping the preceding element to an extent that the straight end edge coincides with a line through said gauge marks on the side edges and each course overlapping the next lower course to the extent of the spacing of said first mentioned gauge mark from the adjacent side edge.

13. Roofing of the character described comprising, in combination, a plurality of overlapping courses of shingle elements, each shingle

element having a straight end edge, parallel side edges of unequal length, and an irregular end edge including a straight portion parallel with said first mentioned end edge and adjacent the longer side edge, said straight portion being of a length equal to the desired amount of overlap in the laying of the shingle elements, a gauge mark on each of the side edges disposed in a line parallel with said straight end edge and with the gauge mark on the shorter side edge spaced from the irregular end edge a distance equal to the straight portion of said irregular end edge, the shingle elements of each course being laid with their side edges parallel and coincident, and with each successive shingle element having its irregular end overlapping the straight end of the preceding element to an extent that the gauge marks of the overlapping element coincide with the straight end edge of the lower element, and each course overlapping the next lower course to the extent of the straight portion of said irregular end edge.

14. Roofing of the character described comprising, in combination, a plurality of overlapping courses of shingle elements, each shingle element having end edges one of which is straight, and parallel side edges extending at

right angles to said straight end edge, a gauge mark projecting from the end edge opposite said straight end edge and spaced from an adjacent side edge a distance equal to the amount of overlap desired in the laying of the shingle elements, a gauge mark on each side edge lying in a line parallel with said straight end edge and spaced inwardly from the end edge bearing said first mentioned gauge mark a distance not less than the spacing of said first mentioned gauge mark from the adjacent side edge, the shingle elements of each course being laid obliquely and with each successive shingle element disposed to overlap with its side a side of the preceding element, the side edge of the upper element abutting the gauge mark on the end edge of the lower element and the end edge of the upper element coinciding with the line through the gauge marks on the side edges of the lower element, and each course overlapping the next lower course to the extent that the straight end edge of each element coincides with the gauge marks in the side edges and so that the side edges coincide with the respective side edges of the lower element.

VERNON TATRO.
